Esq., Atty.

UNITED STATES PATENT OFFICE.

EDWARD J. DECKER, OF PHILADELPHIA, PENNSYLVANIA, ASSIGNOR TO
PAUL S. REEVES, OF PHILADELPHIA, PENNSYLVANIA.

JOURNAL-BEARING.

SPECIFICATION forming part of Letters Patent No. 722,495, dated March 10, 1903.

Application filed November 6, 1902. Serial No. 130,227. (No model.)

To all whom it may concern:

Be it known that I, EDWARD J. DECKER, of the city and county of Philadelphia, State of Pennsylvania, have invented an Improvement in Journal-Bearings, of which the following is a specification.

More particularly, my invention relates to that class of journal-bearings known as "filled" bearings, in which the bearing-face is provided with a series of transverse grooves or pockets containing graphite or other comminuted antifriction material.

The principal objects of my invention are to enable the filling material to be held more firmly in the retaining grooves or pockets and to avoid the formation in the pockets of sharp angles or corners and to brace or strengthen the bearing to resist the tendency to crack longitudinally when subjected to heavy pressure or blows.

In carrying out my invention I form the inner curved or bearing face of a series of transverse ribs, the end ribs of which extend from opposite sides of the bearing to a distance beyond the median line and are connected at their ends with the end walls by a short connecting brace-rib, as is more fully explained hereinafter.

In the drawings, Figure 1 is a perspective view of the casting or shell of my improved car journal-bearing, and Fig. 2 is a plan view of the same.

The shell *a* is a single casting, usually of brass or bronze, having the customary external form and the internal curved bearing-face, which fits the journal. The inside of the casting between the curved end walls *b b* is hollow and is formed with a series of integral curved diagonal parallel ribs *c c*, which form a series of parallel diagonal pockets *d*, adapted to be filled with graphite or any other antifriction filling such as is used in filled bearings. Similar pockets are formed between the end ribs *c' c'* and the end walls *b b*; but these end ribs *c' c'* are not continued entirely across the face of the casting, as are the ribs *c c*, but extend from one side to a distance beyond the median line of the casting and are united at their ends each by a short longitudinal brace-rib *e* with the corresponding end wall *b*. The two end ribs *c' c'* extend from opposite sides

of the casting, so that the short longitudinal brace-ribs *e e* are located one on each side of the median line. This arrangement of the end ribs *c' c'* and brace-pieces *e e* possesses two marked advantages: It avoids the formation of sharp angles or corners in the pockets and it greatly strengthens the casting at the points where strengthening is most required. The greatest strain upon the bearing is usually upon the center line of the casting, and if it is braced only at the center line there is a tendency to crack at one side or the other. The brace-ribs, however, are so located that they brace the casting on each side of the median line and render it much stronger. The ends of the pockets *d d* between diagonal ribs *c c* and between the ribs and the ends *b b* are bridged by strips or ribs *f*, the outer faces of which are curved to correspond with the curvature of the ribs *c c* and ends *b b* and the inner faces of which form ends to the pockets *d* to retain the filling material in place.

The number, size, and direction of the transverse ribs will vary with the size and weight of the bearing and the uses for which it is intended; but in any case the short connecting brace-ribs *e e* between the ends of the outer transverse ribs and the end walls will add two additional elements of strength to the bearing as a whole, and the location of those ribs on opposite sides of the median line and adjacent to it will introduce those elements of strength at the two points where they are most effective.

The details of construction may be varied without departing from my invention.

What I claim as new, and desire to secure by Letters Patent, is as follows:

1. A journal-bearing having a curved inner face adapted to fit the journal and formed with a series of parallel diagonal transverse ribs, the two outer ribs extending from opposite sides to a distance beyond the median line of the bearing and being connected with the end walls by short longitudinal brace-ribs located one on each side of the median line.

2. A journal-bearing having a curved inner face adapted to fit the journal and formed with a series of transverse ribs, the two outer

end ribs extending from opposite sides to a distance beyond the median line of the bearing and being connected with the end walls by short longitudinal brace-ribs located one 5 on each side of the median line.

3. A journal-bearing having a curved inner face adapted to fit the journal and formed with a series of transverse ribs, the two outer end ribs extending from opposite sides to a 10 distance beyond the median line of the bearing and being connected with the end walls by short longitudinal brace-ribs located one

on each side of the median line, said inner face being further provided with longitudinal strips extending over the ends of the transverse ribs and bridging the spaces between them and having a curvature corresponding with the curvature of said transverse ribs. 15

In testimony of which invention I hereunto set my hand.

EDWARD J. DECKER.
